UNITED STATES PATENT OFFICE

ROSE M. GRAVES, OF CHICAGO, ILLINOIS, ASSIGNOR, BY MESNE ASSIGNMENTS, TO ASSOCIATED APPAREL INDUSTRIES, INC., OF CHICAGO, ILLINOIS, A CORPORATION OF ILLINOIS

FOUNDATION GARMENT

Application filed April 20, 1931. Serial No. 531,373.

This invention relates to foundation garments and has for its object to provide a simple form-fitting garment adapted to give a smooth non-bulging line to the figure and thus afford a proper foundation for the outer garments.

Another object of the invention is to provide a light-weight foundation garment adapted to mold the entire figure and support the diaphragm and abdomen, and to provide adjustable means for flattening the diaphragm while allowing perfect freedom of movement to the wearer.

My invention may be applied to any suitable type of corset, combined corset and brassière, or other foundation garment adapted to conform to the contour of the body. An important feature resides in providing a garment of this type with an inside panel adapted to cover the body in the region of the diaphragm and abdomen. This panel is suitably stiffened and is provided at its upper sides with elastic or other bands which project out through openings in the front of the garment and are adapted to be fastened under varying degrees of tension to draw in the diaphragm in accordance with the correct waist measurement of the wearer.

The preferred garment which I have selected to illustrate my invention is a combined corset and brassière having an opening at one side from top to bottom and provided with suitable fastening means. Longitudinal elastic sections at the sides of the garment mold the figure while allowing proper freedom of movement to the wearer. The inside panel which covers the diaphragm and abdomen is concealed beneath a central section which is secured to the front of the garment, and the upper edge of said panel is detached from the brassière so that it may be drawn in or tightened over the diaphragm when tension is applied to its upper edges.

The adjustment of this stiffened panel is preferably controlled by two pairs of elastic straps which are attached to the upper edges of the panel and project out through the openings in the front section of the garment.

The elastic straps of each pair are spaced 50 apart at their points of attachment to the

panel and converge into tabs provided with fastening means such as hooks which co-operate with eyelets formed in tapes secured to the back of the garment. The adjustment of the straps controls the tension on the 55 panel and distributes the flesh of the diaphragm so as to give a smooth, non-bulging line to the figure, the flexibility of the elastic straps preventing binding or discomfort to the wearer.

The invention will be described in connection with the embodiment shown in the accompanying drawings, in which:

Figs. 1 and 2 are front and rear views, respectively, showing the preferred foundation 65 garment in the open position; and

Fig. 3 is a side view of a torso showing the garment applied thereto with the elastic straps adjusted in one of several possible positions.

In the drawings, the garment comprises a front section 1 having a brassière portion 2 secured to its upper edge, a back section 3, and longitudinal side elastic sections 4 and 5 extending from the bottom of the garment 75 to about the waist line where they are secured to upper side sections 6 and 7, respectively, constituting the sides of the brassière. The garment is adapted to encircle the body of the wearer and is fastened by means of a 80 series of hooks 8 on one edge adapted to engage in corresponding eyes 9 on the other edge as shown in Figs. 1 and 2. Adjustable shoulder straps 10 and 11 are fastened by buttons 12 to the upper edge of the brassière 85 portion 2, and by similar buttons 13 to the upper edge of the back section 3, to hold the garment in position on the wearer.

An outer central section or panel 14 is secured to the front section 1 of the garment 90 by rows of stitches 15 which extend around the bottom of section 14 and up the sides to about the waistline, and is also stitched at 16 to the lower edge of the brassière. The upper edges of section 14 lying between the rows 95 of stitches 15 and 16, however, are unattached so as to provide openings 17 leading to the reverse side of the garment for a purpose hereinafter described.

The back section 3 has two double stays 18

of bone or metal which extend the full length of the garment to give it proper rigidity. At the reverse side of the front section 1 is the inside panel 19 adapted to cover the body in the region of the diaphragm and abdomen, and having its sides attached to the corset and its upper edge 20 coincident with but detached from the lower edge 16 of the brassière 2. The panel 19 has three center stays 21 and double side stays 22 and 23, all extending from the bottom of the panel 19 to its upper edge 20 which is approximately at the waist line. When the garment is worn the panel 19 is entirely concealed from view by the central front section 14 as will be seen from Figs. 1 and 3. The absence of stays in the seams 24 and 25 of the garment gives proper freedom to the movement of the chest and arms of the wearer, while the stayed portions 21, 22 and 23 of the panel 19 furnish the strength and rigidity necessary to give the desired abdominal support.

Pairs of elastic straps 26 and 27 are sewed to the upper side edges of the diaphragm control panel 19 in the seams 28 which connect the panel 19 to the main front section 1 of the garment directly beneath the central section 14. The straps 26 and 27 of each pair pass through the openings 17 of the central section 14 and converge into tabs 29 each of which is provided with a hook 30. The elastic straps 26, 27 extend partly around the outer sides of the garment at the waist line, and tapes 31 provided with a plurality of embroidered eyelets 32 are sewed into the vertical seams of the back section 3 and extend forwardly toward the straps 26, 27 for the purpose of adjustably receiving the hooks 30.

In adjusting the garment upon the wearer it is first placed across the back and then circled around the body so that the free edges meet at the left side as shown in Fig. 3, whereupon the series of hooks 8 are clasped in the corresponding eyes 9, and the shoulder straps are also adjusted to secure the garment in position. The diaphragm control is then adjusted by inserting the hooks 30 at the ends of the paired elastic straps 26 and 27 into one or another of the eyelets 32 in the respective tapes 31, drawing in the diaphragm in accordance with the correct waist measurement. The choice of eyelets 32, whether first, second or third, depends upon the amount of flesh in the diaphragm and the particular adjustment or degree of tension desired. The flexibility of the elastic straps 26 and 27 gives comfort to the wearer while distributing the flesh of the diaphragm in such a manner as to give a smooth, unbroken line to the figure.

The garment has single garter straps 33 and 34 attached to the lower edges of the front and rear sections 1 and 3, respectively, and doubled garter straps 35 each with one end attached to the lower edge of the main

front section 1 and the other end attached to the lower edge of the central front section 14. An elastic gore 36 is inserted in the lower central portion of the front section 1, and a similar gore 37 is inserted in the upper central portion of the back section 3.

The garment may be made of any suitable material, but to give a pleasing appearance the entire garment, with the exception of the elastic inserts 4 and 5, front brassière portion 2, and inside panel 19, may be made of brocaded cloth. The front brassière portion 2 may be made of ribbed mercerized cloth, while the inside panel 19 may be made of sateen if desired.

It will be evident that various changes may be made in the details of construction herein shown and described without departing from the scope and spirit of the invention as defined in the appended claims.

The invention claimed is:

1. A foundation garment adapted to encircle the body of the wearer and having a stiffened panel arranged to cover the diaphragm and abdomen, a central section secured to the front of the garment concealing said panel and having openings in the sides at about the waist line, elastic straps secured to the sides of said panel and extending through the openings in said central section and partly around the outer sides of the garment at the waist line, tapes secured to the back portion of the garment and arranged to extend forwardly toward said elastic straps, and means for adjustably securing said elastic straps to said tapes to hold said panel under tension.

2. A form-fitting foundation garment comprising a corset and a brassière adapted to encircle the body and having an opening at one side, fastening means for securing adjacent edges of said opening together, longitudinal side elastic sections extending from the bottom of the garment to about the waist line, a stiffened panel arranged to cover the diaphragm and abdomen, a central section secured to the front of the garment concealing said panel and having openings in the sides at about the waist line, elastic straps secured to the sides of said panel and extending through the openings in said central section and partly around the outer sides of the garment at the waist line, tapes having a plurality of spaced eyelets secured to the back portion of the garment and arranged to extend forwardly toward said elastic straps, and hooks on said elastic straps adapted for selective engagement with the eyelets in said tapes to hold said panel under tension.

3. A foundation garment comprising a corset and a brassière adapted to encircle the body and having an opening at one side, fastening means for securing adjacent edges of said opening together, a stiffened panel in the corset arranged to cover the dia-

phragm and abdomen and having its sides attached to the corset and its upper edge coincident with and detached from the lower edge of the brassière, a central section secured to the front of the corset and lower edge of the brassière in position to conceal said stiffened panel and having openings at the sides leading to the reverse side of the garment at about the waist line, straps secured to the sides of said stiffened panel and extending through the openings in said central section and at least partly around the outer sides of the garment, and means for holding said straps under tension.

5. 4. A foundation garment comprising a corset and a brassière adapted to encircle the body and having an opening at one side, fastening means for securing adjacent edges of said opening together, a stiffened panel in the corset arranged to cover the diaphragm and abdomen and having its upper edge coincident with and detached from the lower edge of the brassière, a central section secured to the front of the corset and lower edge of the brassière in position to conceal said stiffened panel and having openings at the sides leading to the reverse side of the garment at about the waist line, pairs of elastic straps secured to the sides of said stiffened panel and extending through the openings in said central section and partly around the outer sides of the garment, the straps of each pair converging into a common point, tapes secured to the back portion of the garment and arranged to extend forwardly toward said elastic straps, and means for adjustably securing said elastic straps to said tapes to hold said stiffened panel under tension.

5. A foundation garment comprising a corset and a brassière adapted to encircle the body and having an opening at one side, fastening means for securing adjacent edges of said opening together, a stiffened panel in the corset arranged to cover the diaphragm and abdomen and having its sides attached to the corset and its upper edge coincident with and detached from the lower edge of the brassière, and means controlled from the outside of the garment for exerting tension on the sides of said stiffened panel.

Signed at Chicago in the county of Cook and State of Illinois this 15th day of April A. D. 1931.

ROSE M. GRAVES.
